[57] CLAIM

The ornamental design for a tablet, as shown and described.

DESCRIPTION

FIG. 1 is a top plan view of a tablet showing our new design;

FIG. 2 is a front elevational view thereof;

FIG. 3 is a right side elevational view thereof, the left side elevational view being the same in appearance;

FIG. 4 is a bottom plan view thereof;

FIG. 5 is a sectioned right side elevation view thereof, taken along section line 5—5 of FIG. 1;

FIG. 6 is a sectioned front elevation view thereof, taken along section line 6—6 of FIG. 3; and,

FIG. 7 is a rear elevational view thereof.
